UNITED STATES PATENT OFFICE.

CHARLES E. CHAPMAN, OF FORT EDWARD, NEW YORK, ASSIGNOR OF ONE-HALF TO
JOSEPH GOODFELLOW, OF FORT EDWARD, NEW YORK.

SUPERHEATER.

Application filed October 29, 1920. Serial No. 420,481.

To all whom it may concern:

Be it known that I, CHARLES E. CHAPMAN, citizen of the United States, residing at Fort Edward, in the county of Washington and State of New York, have invented certain new and useful Improvements in Superheaters, of which the following is a specification.

This invention relates to a superheater adapted for attachment to internal combustion engines for the purpose of utilizing the exhaust heat from the engine for heating and mixing air and steam and supplying the same to the carbureted air forming the explosive mixture used in an internal combustion engine.

In detail, the invention consists of a unit superheater feeding to the air intake of the carburetor or other fuel mixture forming device a thorough mixture of superheated air and steam resulting from passing air and steam through separate tubular compartments around which exhaust gases from the engine are circulated, such compartments each containing a group of flues or tubes.

A further feature of the invention is the provision of means for keeping separate the air and steam during passage through the superheater and then thoroughly mixing the superheated products after passage through the superheater tubes.

In the drawings:

Figure 1 is a vertical longitudinal section through the superheater,

Figure 2 is a transverse section in a vertical plane on the line 2—2 of Figure 1.

The invention, as herein shown, comprises a rectangular shell 1 flanged at each end as indicated at 2 to receive tube sheets 4 and 5 which are perforated for mounting the superheater tubes 6. The shell 1, next to the sheet 4, is perforated as shown at 7' to permit the escape of exhaust gases and nipples 7 and 8 admit exhaust gases direct from the exhaust pipe and from a secondary superheater, respectively. One side of the superheater shell 1 is provided with tracks 9 in which the side 10 slides to provide for removing said side for cleaning the superheater tubes 6 of soot formation.

On the inlet end and abutting the sheet 4 is a rectangular end unit 11 closed by a cover plate 12 to form a receiving chamber,

the unit being clamped between the plate and said sheet by bolts 13 extending through the plate, sheet and adjacent flange 2. The cover plate 12 has openings 14 and 15 for steam and air respectively 60 and which are separated from each other by a partition 16 extending between the tube sheet 4 and cover plate dividing the chamber into compartments.

At the opposite end of the superheater, a 65 similar rectangular end unit 17 and cover plate 18 provide a mixing chamber and are secured by bolts 19 extending through the cover plate, tube sheet and adjacent flange 2. The cover plate 18 has a nipple 70 20 which may be connected to the air intake of a carburetor while, within the mixing chamber, said plate carries supports 21 mounting a conical deflector 22 disposed opposite the nipple to overlie the outlet 75 opening of the chamber.

The air and steam enter separately as indicated at 14 and 15 and pass through the superheater tubes 6 which, by reason of the partition 16, are divided into two 80 groups. The exhaust gases entering at 7 and 8 pass around the superheater tubes thoroughly superheating the air and steam and are emitted through the openings 7'. The air and steam leave the superheater 85 tubes at the tube sheet 5 and enter the mixing chamber 17 but are prevented from directly passing out by reason of the baffle 22 against which they impinge, the flow being obstructed sufficiently to permit the air 90 and steam to mingle in a homogeneous mixture. The mixture thus formed passes out as indicated by the arrows, beneath the deflector 22 and enters the air intake passage of the carburetor. 95

It will be seen from the foregoing, that the superheater herein described, provides a means of supplying a highly heated mixture of comingled air and steam to the carburetor of an internal combustion engine 100 and such mixture is particularly adapted for use in apparatus for burning coal oil and the like in motor vehicles.

Having thus described the invention, what is claimed as new is:

1. A superheater for air and steam comprising separate groups of superheater tubes, means for feeding steam through one group, means for feeding air through another group, and a mixing chamber com- 110

mon to the groups for receiving the discharge therefrom to come into within the chamber.

2. A superheater for air and steam comprising separate groups of superheater tubes, means for feeding steam through one group, means for feeding air through another group, a mixing chamber common to the groups for receiving the discharge therefrom to come into within the chamber, and a baffle within the chamber for diverting the flow of both air and steam.

3. A superheater for air and steam comprising separate groups of superheater tubes, means for feeding steam through one group, means for feeding air through another group, a mixing chamber common to the groups for receiving the discharge therefrom to come into within the chamber, the chamber being provided with an outlet, and a baffle within the chamber overlying said outlet.

4. A superheater for air and steam comprising separate groups of superheater tubes, chambers at opposite ends of the

tubes, and means dividing one of said chambers into a steam compartment for feeding steam to one group of tubes and an air compartment for feeding air to another group of tubes, the other of said chambers being common to the tubes for receiving the discharge therefrom to mingle within such chamber.

5. A superheater for air and steam comprising separate groups of superheater tubes, chambers at opposite ends of the tubes, means dividing one of said chambers into a steam compartment for feeding steam to one group of tubes and an air compartment for feeding air to another group of tubes, the other of said chambers being common to the tubes for receiving the discharge therefrom to mingle within such chamber, the latter chamber being provided with an outlet, and a baffle mounted in juxtaposition to said outlet.

In testimony whereof I affix my signature.

CHARLES E. CHAPMAN. [L.S.]
